UNITED STATES PATENT OFFICE.

WILLIAM NOTHAFT AND GEORGE R. HARRISON, OF PHILADELPHIA, PENNSYLVANIA.

FIRE-ESCAPE.

1,032,294.

Specification of Letters Patent.

Patented July 9, 1912.

Application filed April 16, 1912. Serial No. 691,159.

To all whom it may concern:

Be it known that we, WILLIAM NOTHAFT and GEORGE R. HARRISON, citizens of the United States of America, and residents of the city of Philadelphia, in the State of Pennsylvania, have jointly invented a new and useful Improvement in Fire-Escapes, of which the following is a specification.

This invention relates to "rope-grip" fire-escape devices, and consists in an improved fire-escape device of that type, and in certain novel combinations of parts embodied therein, as hereinafter particularly described and claimed.

15 The leading objects of this invention are to protect the hands from the heat due to the frictional rubbing contact of the jaws with the rope, and to protect the rope against undue wear by such contact.

20 Other objects will be set forth in the general description which follows.

A sheet of drawings accompanies this specification as part thereof.

Figure 1 is an elevation, partly in section of the improved fire escape in use; Figs. 2 and 3 are side views projected from Fig. 1; Fig. 4 represents a cross section on the line A—B, Fig. 1; Fig. 5 represents a cross section on the line C—D, Fig. 1.

30 Like reference characters refer to like parts in all the figures.

The improved fire-escape device is composed of a pair of rope-gripping jaws, 1 and 2, of oak or other suitable wood; a U-shaped metallic clip, 3, adapted to embrace both jaws at one point near the upper end of the device; a clamping screw 4 interacting with the closed end of said clip 3 and with the back of the jaw 1; a U-shaped metallic clip, 5, adapted to connect the jaws at a subjacent point, at or above midlength, a cam lever, 6, fulcrumed between the ends of said clip 5 and interacting with the back of said jaw 2; and suitable means for attaching the person to the pair of jaws, represented in Figs. 1-3 by a leather strap 7 fixedly attached by wood screws to one of the jaws and adapted to form a stirrup or body-embracing loop 7', and a ring, 8, attached in like manner and adapted to interlock with the customary snap hook on a fireman's belt, or to be utilized in like manner. The jaws 1 and 2 are preferably and conveniently of one and the same pattern and constructed with longitudinal face grooves fitted to the rope α , Fig. 1 which they are to frictionally

grip, and internally smooth, and with backs adapted jointly to form an amply long grasping or handle portion, 1' 2', shown in section in Fig. 1, adapted to be grasped by the left hand of a person using the device. Each of the jaws 1 and 2 is further constructed with a pair of side grooves, 9, in a rectangular portion fitted to the legs of the screw-clamp clip 3, and with parallel slots, 10, extending through the jaws at the sides of its face groove, and fitted to the legs of the lever-clamp clip 5. Said legs of the screw-clamp clip 3 are each constructed with a longitudinal slot, 11, through which a wood screw, 12, enters the jaw 1 to attach the clip thereto, and with an out-turned and apertured catch end 13 with which a catch pin, 14, fast in the jaw 2 interlocks. See Fig. 4. The legs of the lever-clamp clip 5 extending through both jaws have apertured ends, 15, between which the cam lever 6 is fulcrumed as aforesaid by a removable pivot, 16. This pivot is shown as a bolt with milled head and nut. It may be of any known or improved form, and other like modifications in mechanical details will suggest themselves to those skilled in the art. By removing said pivot 16 and springing apart said catch ends 13 of the clip 3, the jaws 1 and 2 may be quickly separated to remove the device from the rope α or to admit the rope.

On applying the device to the rope the jaws are sufficiently tightened by means of the screw clamp to adapt the device to suspend a minimum weight, so that a child, for example, attached thereto will descend the stationary rope at a safe rate of speed without any operation on its part. A heavier person, grasping the handle portion 1' 2' with the left hand and manipulating the clamping lever 6 by means of the right hand, may additionally tighten the jaws upon the rope as may be required to resist excessive speed of descent. One or both feet may occupy the loop 7' of the strap 7 or the loop may be enlarged to embrace the body beneath the arms; or the ring 8 may be utilized by a fireman in customary manner while he grasps the handle portion 1' 2' of the device with one hand and assists a lady or child with the other.

The wooden jaws 1 and 2 being poor conductors of heat are not liable to be heated by friction so as to burn the hands of a person using the device; and their smooth

grooves form a frictional bore within which the rope *a* is effectively gripped without undue wear. The distribution of the frictional contact throughout practically the entire length of the jaws when the handle portion 1' 2' is grasped and when the cam lever 6 is manipulated is also advantageous.

Having thus described said improvement, we claim as our invention, and desire to patent under this specification—

1. A rope-grip fire-escape of the within described type having, in combination with a stationary rope, a pair of long wooden jaws grooved to frictionally embrace the 15 rope between them, a U-shaped clip embracing the two jaws near the upper end of each of them, a clamping screw interacting with the closed end of this clip and with the back of one of the jaws, a second U-shaped clip 20 extending through the two jaws at a subjacent point, and a cam lever fulcrumed between the ends of the clip last named and interacting with the back of the other jaw; said jaws having a grasping portion of 25 ample length below said last-named clip, and means for attaching a person thereto.

2. The combination, in a rope-grip fire-escape device, of a pair of wooden jaws grooved to frictionally embrace the rope between them and having a rectangular por- 30

tion provided with side grooves, a U-shaped metallic clip embracing said rectangular portion and constructed with legs slidably fitted to said side grooves and provided with longitudinal slots and catch holes, wood 35 screws extending through said slots into one of the jaws, catch members carried by the other jaw and constructed and arranged to interlock with said catch holes, and a clamping screw interacting with the closed end of 40 said clip and with the back of the contiguous jaw.

3. The combination, in a rope-grip fire-escape device, of a pair of wooden jaws grooved to frictionally embrace the rope between them and having a pair of slots extending through both jaws at the sides of the rope-embracing grooves, a U-shaped metallic clip the legs of which extend through said slots, and a clamping lever having a 45 cam end removably pivoted between the ends of said legs and adapted to interact with the back of the adjoining jaw, substantially as hereinbefore specified.
